(57) **CLAIM**

The ornamental design for a fluid applicator, as shown and described.

DESCRIPTION

FIG. 1 is a perspective view of a fluid applicator showing our new design in an assembled format;

FIG. 2 is a front elevation view thereof;

FIG. 3 is a first side elevation view thereof;

FIG. 4 is a second side elevation view thereof;

FIG. 5 is a rear view thereof;

FIG. 6 is a bottom view thereof;

FIG. 7 is a top view thereof;

FIG. 8 is an exploded perspective view of the fluid applicator of FIG. 1;

FIG. 9 is a front elevation view of the fluid applicator of FIG. 8;

FIG. 10 is a first side elevation view of the fluid applicator of FIG. 8; and,

FIG. 11 is a second side elevation view of the fluid applicator of FIG. 8.

The contour lines shown on the fluid applicator are presented to indicate the presence of surface contours. The broken lines shown in the drawings illustrate portions of the fluid applicator that form no part of the claimed design.
